UNITED STATES PATENT OFFICE.

ALICE M. HAMILTON AND WILLIAM C. HAMILTON, OF PACIFIC BEACH, CALIFORNIA;
SAID WILLIAM C. HAMILTON ASSIGNOR TO SAID ALICE M. HAMILTON.

DESIGN FOR ADVERTISING STRUCTURE.

Application filed September 24, 1928. Serial No. 28,267. Term of patent 14 years.

To all whom it may concern:

Be it known that we, ALICE M. HAMILTON and WILLIAM C. HAMILTON, citizens of the United States, residing at Pacific Beach, in the county of San Diego and State of California, have invented a new, original, and ornamental Design for an Advertising Structure, of which the following is a specification, reference being had to the accompanying drawings, forming a part thereof.

Figure 1 is a perspective view of our new

design for an advertising structure, and Fig. 2 is a sectional view on a reduced scale through 2—2 of Fig. 1.

We claim:

The ornamental design for advertising structure, substantially as shown.

In testimony whereof, we have hereunto set our hands at San Diego, California, this 18th day of September, 1928.

ALICE M. HAMILTON.
WILLIAM C. HAMILTON.
